UNITED STATES PATENT OFFICE.

FRED L. SWARTZ, OF TOLEDO, OHIO, ASSIGNOR OF ONE-HALF TO GEORGE MONTVILLE, OF TOLEDO, OHIO; EMMA MONTVILLE ADMINISTRATRIX OF SAID GEORGE MONTVILLE, DECEASED.

AUTOMATIC DOOR OPERATING AND CONTROLLING MEANS.

Application filed March 19, 1921. Serial No. 453,673.

To all whom it may concern:

Be it known that I, FRED L. SWARTZ, a citizen of the United States, residing at Toledo, in the county of Lucas and State of Ohio, have invented certain new and useful Improvements in Automatic Door Operating and Controlling Means, of which the following is a specification, reference being had therein to the accompanying drawing.

10 This invention relates to improvements in automatic door operating and controlling means, and more particularly to means for controlling and operating the doors on garages or the like, which are put into automatic action by the wheel of the vehicle entering or leaving the building.

15 The object of the invention is to provide means whereby the doors of a garage can be both automatically opened and closed from within or without the building.

20 A further object of the invention is to provide a mechanism so constructed that the doors when closed are automatically locked or latched in closed position.

25 A still further object of the invention is to provide automatic means for lighting a light within the building, worked in conjunction with the door operating means so as to provide light when the vehicle enters or leaves the building.

30 A still further object of the invention is to provide a means for automatically operating doors, which is simple of construction, cheap of manufacture and highly efficient in operation.

35 Other and further objects of the invention will appear in the following description and specification, and in the drawings in which—

40 Figure 1 is a vertical sectional view taken longitudinally the garage, floor and doors, the door and light operating means being shown in full lines.

45 Figure 2 is a top plan view of the improved door-operating means showing its installation.

50 Referring now to the drawings in which like parts are designated by similar reference numerals, 1 represents the walls of a building which is provided with double doors 2, and a floor 3 which is preferably con-

crete, although any other type of floor can be readily used.

The greater part of the door and light operating mechanism is within the space 4 below the floor 3.

At the outer side of the doors and protruding through suitable openings 5 in the floor are two traps or deppressible platforms 6 and 7. The trap 6 is in position to be readily struck by the left wheel of the vehicle when entering the building, while the trap 7 is positioned to be struck by the right wheel of the vehicle when leaving the building. To facilitate striking the traps, they are positioned slightly to the left and right of the center of the doors or floor. These traps are preferably about twelve inches long, one inch wide and eight inches deep and have their protruding ends beveled, as shown. By making the traps approximately these dimensions and positioned as stated, the distance from the outer edge of one trap to the outer edge of the other is less than the width of the average tread of an automobile, so that when the left wheel of the vehicle strikes the trap 6, the right wheels of the vehicle will entirely miss the trap 7.

Within the building and, preferably to the left of the center thereof, two traps 8 and 9 protrude through the floor 3 and are positioned one in front of the other, as clearly shown.

A foundation or block 10 is positioned within the space 4 and below the traps 6 and 7. Extending in parallel separated relation between the block 10 and the bottom of the trap 6 are two posts 11, having coiled thereabout the springs 12, the ends of which abut the block and the bottom of the trap. Extending from the center of the bottom of the trap 6 is a rod 13, the lower end of which is provided with a slot opening 14 of a length equal to the distance the trap 6 protrudes above the floor 3.

Extending transverse the block 10 is a shaft 15, fastened at its ends in the bearings 16 carried upon raised portions 17 of the block 10, and journaled at its center in bearing 18 carried upon a raised block portion 18'.

A crank arm 19 having a notched end 20

is suitably fastened within the slot 14 of the trap rod 13 by a pin or the like, and has its other end suitably fastened to the shaft 15.

The trap 7 is provided with a downwardly extending rod 22, suitably fastened to the bottom of the trap, as at 23, and having in its lower end a slot 24. A rod 25 has its one end connected to the shaft 15, as at 26, and its other end 27 notched and fastened within the slot 24, by means of a pin 28.

Positioned within the space 4 and extending transverse the garage below the traps 8 and 9, is a block or foundation 29 having raised end portions 30. A shaft 31, provided with upwardly extending ends 33, extends across the block 29 and is carried within bearings 32, upon the raised portions 30 thereof.

Joining the shafts 15 and 31, are a series of rods 34, 35, 36, 37 and 38. The rod 34 has its lower end 39 fastened to the shaft 15, as shown, and extends vertically upward therefrom and its upper end is fastened within the forked end 40 of the rod 35, by means of a pin 41. The opposite end of the rod 35 is forked, as at 42, and fastened within the fork by means of a pin 43 is the end 44 of the rod 36, which rod is suspended below the floor 3, by means of the bearings 45.

The opposite ends 46 of the rod 36 is fastened within the forked end 47 of the rod 37, by means of a pin 48. The opposite end 49 of the rod 37 is forked as shown, and fastened therein by means of the pin 50 is one end of the rod 38, while the other end of this rod is fastened to the shaft 31, as shown at 51.

Fastened to the shaft 31, at the point 52, and extending transverse the shaft is a rod 53, to the opposite ends of which are fastened the rods 54 and 55, which have their upper ends fastened to the lower portions 56 and 57 of the traps 8 and 9 respectively.

As clearly shown in the drawing, the upper ends 33 of the shaft 31, extend to a point well above the floor 3 of the garage.

Extending parallel the opposite walls of the garage are rods 58 having flattened portions 59, provided with shoulders 60 and 61. The portions 59 of these rods are within the forked end 62 of the upwardly extending shaft 33, and locked therein by means of pins 63 which extend through the fork at a point above the portions 59. The opposite ends 64 of the rods 58 are forked. The rods 65 are fastened at one end within the forks 64, by means of the pins 66, while their opposite ends are provided with a series of holes 67. Suitably fastened to the insides of the doors 2, are inwardly extending L-shaped members 68 having upwardly extending ends 69. The rods 65 are fastened to the members 68 by dropping one of the holes 65 over the ends 69 of the members 68.

Carried upon the bottom of the garage

doors is a pawl 70, pivotally mounted at 71, upon the door. Extending through the floor 3, at a point below the pawl 70 is a rod 72, the upper end of which engages the hooked end 73 of the pawl, while the lower end 75 thereof is forked and passes over the rod 36, which reciprocates therein and is held in place by a pin 76. The rod 36 at a point adjacent its engagement with the rod 72 is bent out of alinement to form a downwardly protruding bulge 77. The operation of this latch will be described later when the general operation of the entire invention is given.

Suitably situated within the garage is a light 78, one of the wires 79 providing current thereto, leads to a switch A, intended to be conveniently located within the house, while the other wire 80, providing current to the light, leads to the post 81, which is mounted upon the block 10. Pivotally mounted as at 82, upon this post is a knife 83, which is adapted to engage the forked terminal post 84. A lead wire 85 connects the terminal 84 and the switch A, which makes a complete circuit to the light 78 when the knife 83 is in engagement with the terminal 84. Journaled through the raised block portion 18' is an S-shaped member 86 having a flattened and enlarged end 87, which is directly below and in engagement with the end of the trap rod 22, while its opposite end 88 extends beneath the enlarged flattened end 89 of the knife 83. The weight of the trap 7 and its downwardly extending rod 22 depresses the S-shaped member 86, so as to normally hold the knife 83 in a raised position, as shown in Fig. 1, out of contact with the terminal post 84. Attention is directed to the fact that the end 89 of the knife 83 is directly beneath and in line with the end of the trap rod 13. The operation of the automatic lighting means will be described when the operation of the entire invention is given.

Having described the mechanism employed to automatically open and close the doors of the garage either from within or without the building; described the door latching means and the lighting operating means, I will now describe the operation of the entire invention, stating the manner in which the doors are automatically unlatched, opened and the light within the building lighted.

When the parts are in the position shown in Fig. 1, the building is vacant and the doors are in a closed position. As the vehicle approaches the doors of the building the driver directs the machine so that the left front wheel of the vehicle will strike the protruding trap member 6, and the weight of the machine upon this trap will depress it against the tension of the coiled springs 12 and as the trap 6 and its downwardly extending rod 13 descend, the rod 19 will be de-

pressed and the shaft 15 rotated. As the shaft 15 rotates, it through the medium of the rods 34, 35, 36, 37 and 38 rotates the shaft 31, which throws the upwardly extending ends 33 thereof in a direction towards the doors. As the ends 62 of the shaft 33 strike the shoulders 61, of the rods 58, an outward motion is imparted to them which through the medium of the rods 65 and the door member 68, swing the doors into open position. At the same time this occurs, the rod 36 is reciprocated in the forked lower end of the rod 72 and the bulged portion 77 strikes the pin 76 and 10 presses the rod 72 to a position to carry the upper end of the rod out of engagement with the end 73 of the door pawl 70. Due to the lost motion caused by the distance between the shoulders 61 and 62 of the rods 20 58, the rod 36 reciprocates within the rod 72 and releases the door pawl before the shaft 33 gives an outward movement to the rods 58.

Except when depressed by the weight of 25 a machine, or the like, the trap 6 is normally up. After the doors have been opened by depressing the trap 6, and the weight of the machine is removed from this trap, the coil springs 12 will raise the trap 6. This action 30 of the springs 12 upon the trap 6 will not reverse the mechanism and close the doors because the movement is taken care of by the slot opening 14 in the rod 13 and the slot 24 in the rod 22, and, therefore, has no 35 affect on the rest of the door operating mechanism.

Also as the foregoing operations take place, the end 89 of the knife 83 is struck by the end of the descending trap-rod 13 and 40 carried downward and into engagement with the terminal post 84, thus completing the electric circuit and lighting the light within the building.

When the machine is within the building, 45 the left front wheel passes over the trap 8, which has been carried downward (and remains in that position) by the operation which opened the doors. This same operation has raised the trap 9 which the front 50 wheel of the machine now strikes and depresses. When the trap 9 is depressed the opposite motion is imparted to the mechanism and the doors are closed, and the latch rod raised to engagement with the 55 door pawl 70. As the doors close the rod 36 moves inwardly, the bulged portion 77 thereof moving out of engagement with the pin 76 of the rod 72. The continued inward movement brings the straight portion 60 of the rod 36 into engagement with the fork of the rod 72 and raises it to engage the pawl 70 of the door. It will be noted that the knife 83 is still in engagement with the terminal post 84 after the machine is within 65 the building and the doors closed. The

driver will then make his exit from the building by means of the supplemental door 2' and when he reaches the house, extinguish the light in the garage by snapping of the switch A.

When the driver intends to take the machine from the garage, he will turn on the switch A and thus light the light within the garage. As the driver backs the machine from the building, the front wheel strikes 70 the trap 8, which assumed a raised position when the garage doors were closed behind the machine. As the trap 8 is depressed, the doors 2 are opened and the trap 7 raised to an elevated position. The right front wheel 75 is now directed so as to hit and depress the trap 7 while the left wheels pass to the left and miss the raised trap 6 entirely. When the trap 7 is depressed, the doors are closed, the rod 72 carried to a raised position and 80 in engagement with the door pawl 70, while the end 87 of the S-shaped rod 86 is depressed thus lifting the opposite end of the S-shaped rod and carrying the knife 83 upward and out of engagement with the terminal post 84, and thereby breaking the 85 electric circuit and extinguishing the light within the building.

Adjustment of the mechanism is obtained 90 by reason of the several holes 67 in the rod 65, and by means of which the lost motion of the apparatus can be increased or decreased.

Attention is also directed to the fact that when the vehicle is within the building and 100 one of its wheels rest upon the trap 9, the doors are doubly latched by reason of the pawl 70 and the latch-rod 72, and the weight of the machine upon the trap 9. With the machine resting upon the trap 9, the 105 mechanism cannot be operated from without the building unless the machine driven upon the raised trap 6 was of greater weight than the machine within the building, in fact of sufficient greater weight as to lift 110 the machine in the building and also depress the coil springs 12.

Having thus described my invention, what I claim and desire to secure by Letters Patent is:—

1. In a door operating mechanism, the combination with the swinging door, of separate depressable door opening members located at opposite sides of the door and operatively connected therewith, separate depressable door closing members located at opposite sides of the door, and operatively connected therewith for closing the door, the depressable members without the door in staggered relation, and the depressable members on the inner side of the door located one directly in front of the other, for the purpose described.

2. In a garage door operating mechanism, a pair of shafts extending transversely of 130

the roadway, one at each side of the door, a pair of depressible members operatively connected to each of said shafts to rotate them, means for connecting said shafts for simultaneous actuation, and means operatively connecting one of said shafts to the door, for the purpose described.

3. In a garage door operating mechanism, a pair of shafts extending transversely of the roadway, one at each side of the door, a pair of depressible members connected to oppositely extending radial arms on each of said shafts, means for connecting said shafts for simultaneous actuation, and means operatively connecting one of said shafts to the other.

4. In a garage door operating mechanism, a pair of shafts extending transversely of the roadway, one at each side of the door, a pair of depressible members operatively connected to each of said shafts to rotate them, means for connecting said shafts for simultaneous actuation, said means carrying a device for controlling the latching and unlatching of the door, and means opera-

tively connecting one of said shafts to the door.

5. In a garage door operating mechanism, a pair of shafts extending transversely the roadway, one at each side of the door, a pair of depressible members connected to oppositely extending radial arms on each of said shafts, reciprocating means connecting said shafts for simultaneous actuation, and means operatively connecting one of said shafts to the door.

6. In a garage door operating mechanism, a pair of shafts extending transversely of the roadway, one at each side of the door, a pair of depressible members connected to oppositely extending radial arms on each of said shafts, reciprocating means connecting said shafts for simultaneous actuation, said reciprocating means carrying a cam for controlling the latching and unlatching of the door and means operatively connecting one of said shafts to the door.

In testimony whereof I hereunto affix my signature.

FRED L. SWARTZ.
